UNITED STATES PATENT OFFICE.

ARTHUR J. THOMAS, OF HARVEY, ILLINOIS.

TRANSMISSION-GEARING FOR HOISTS.

No. 884,777.

Specification of Letters Patent.

Patented April 14, 1908.

Application filed March 1, 1907. Serial No. 359,987.

To all whom it may concern:

Be it known that I, ARTHUR J. THOMAS, a citizen of the United States, residing at Harvey, county of Cook, State of Illinois, have 5 invented a certain new and useful Improvement in Transmission-Gearing for Hoists, and declare the following to be a full, clear, and exact description of the same, such as will enable others skilled in the art to which 10 it pertains to make and use the same, reference being had to the accompanying drawings, which form a part of this specification.

My invention relates in general to hoisting apparatus and more particularly to transmission gearing for hoists.

Hoists for raising and lowering loads, such as those with which traveling cranes are provided, must be capable of readily elevating or lowering the load and of automatically 20 sustaining the load at any desired height, as for instance while the load is being transported by the crane.

The primary object of my invention is to provide a hoist of the type above mentioned 25 which will be simple and compact in construction, easily and positively operated, and convenient and efficient in use.

The embodiment of my invention herein disclosed may be generally described as comprising a rotary power shaft, a pair of pinions loosely mounted upon the power shaft, a clutch member surrounding and rotating with the power shaft intermediate of the pinion, clutch members on the pinions with one 35 of which the first clutch member engages when the power shaft rotates in one direction, and with the other of which the first clutch member engages when the power shaft rotates in an opposite direction, a rotary hoisting shaft having fixed thereon a gear wheel meshing with one of said pinions, a second gear wheel meshing with the other pinion and having an interiorly screw-threaded hub engaged with a screw thread 40 45 50

transmitting motion from the hoisting shaft to a load which is to be raised, lowered, or held at a given elevation.

My invention will be more fully described hereinafter with reference to the accompanying drawing in which the same is illustrated as embodied in a convenient and practical form, and in which

Figure 1 is a sectional view on line 1—1 Fig. 2; Fig. 2 a sectional view on line 2—2 Fig. 1; Fig. 3 a plan view of the clutch and pinions removed from the power shaft; Fig. 4 a plan view of a modified form of clutch for alternately locking the pinions to the power shaft; and Fig. 5 a sectional view on line 5—5 Fig. 4.

The same reference characters are used to designate the same parts in the several figures of the drawing.

Reference character A designates a rotary power shaft which may be driven by any suitable means not shown.

Reference characters B' and B² designate the two parts of a casing through which the power shaft extends. The two parts of the casing may be detachably secured together in any suitable manner, as by means of flanges through registering holes in which bolts b extend. The lower part B² of the casing may conveniently be provided with feet B, B by means of which the casing and hoisting mechanism contained therein may be secured to a support.

Fixed upon the power shaft A in any suitable manner as by means of a key c is a clutch member C having lugs c' and c² projecting laterally from the opposite sides thereof. Loosely surrounding the power shaft are pinions D' and D² located on the opposite sides of the clutch member and intermediate of the same and the bearings in the casing surrounding the power shaft. Lugs d' and d² project inwardly from and are fixed to the pinions D' and D². The lugs d' and d² are so located relatively to the lugs c' and c² on the clutch member that a rotation of the power shaft in the direction of the arrow will bring the lug c' into engagement with the lug d' while a rotation of the power shaft in an opposite direction will bring the lug c² into engagement with the lug d².

E designates a hoisting shaft which ex-

tends through the casing and is journaled in bearings formed between the two portions thereof.

5 E' designates a gear wheel fixed upon the hoisting shaft E as by means of a key e'. The gear wheel E' meshes with the pinion D'.

E² designates a second gear wheel which surrounds the hoisting shaft E and is provided with an interiorly screw-threaded hub 13 e² engaging a screw-thread f² on the hoisting shaft. The gear wheel E² meshes with the pinion D².

15 F designates a collar clamped to the hoisting shaft E and provided with a lug f projecting laterally towards the hub of the gear wheel E².

20 f' designates a lug on the hub e² of the gear wheel E², which projects outwardly so as to engage the lug f when the gear wheel has moved axially a predetermined distance upon the shaft E.

25 G designates a disk surrounding the hoisting shaft and locked to rotate therewith in any suitable manner, as by means of grooves g in the disk engaging ribs e' on the hub of the gear wheel E'. Located on opposite sides of the disk G are coöperating disks G' and G² which are locked against rotation in any suitable manner as by means of lugs g', g' 30 projecting radially from their outer peripheries and engaging stops b' on the inner surface of the upper part B' of the casing and lugs b², b² projecting inwardly from the lower part B² of the casing. Fiber washers h are 35 interposed between the adjacent surfaces of the friction disks G, G' and G², and also between the adjacent surfaces of gear wheels E' and E² and the adjacent surfaces of the friction disks G' and G².

40 H indicates a gear wheel which may form part of a differential gearing for applying the rotary motion of the shaft E to a drum or other means (not shown) for raising or lowering a load.

45 The pinion D² is provided with a sleeve d³ rotating therewith and extending around the shaft A to the outside of the casing. A fly wheel D³ is secured upon the outer end of the sleeve d³.

50 The operation of my invention is as follows, when it is desired to rotate the hoisting shaft E in a direction to raise a load the power shaft is rotated in the direction of the arrow. The initial rotation of the shaft A 55 in such direction brings the lug c' on the clutch member C into contact with the lug d' on the pinion D' so that the gear wheel E' is rotated and therewith the shaft E in the direction of the arrow. When the load is elevated to the desired height the rotation of the power shaft is discontinued. The load is held at such height by means of the friction disks which constitute a brake. A slight 60 rotation of the shaft E by reason of the weight of the load in a direction opposite to

that caused by the rotation of the shaft A in the direction of the arrow causes the rotation of the screw-thread f² within the screw-threaded hub e² of the gear wheel E², to move the gear wheel E², towards the gear wheel E' 70 thereby forcing the friction disks into close contact and locking the shaft to the stationary casing. The weight of the fly wheel D³ as well as the friction of the sleeve d³ and pinion D² upon the shaft A prevent the gear wheel E² from rotating with the hoisting shaft E when it is rotated by the load so that the shaft rotates within the hub of the gear wheel E² and applies the brake. 75

80 When it is desired to lower the load the shaft A is rotated in an opposite direction to that indicated by the arrow which brings the lug c' on the clutch member C into engagement with the lug d' on the pinion D², thereby rotating such pinion with the power shaft and 85 communicating rotary motion to the gear wheel E². Such rotary motion of the gear wheel E² moves the same axially away from the gear wheel E' through the engagement of the screw-threads within its hub with the 90 screw-thread on the shaft E. The weight of the load then rotates the shaft E in a direction to lower the load, the continued rotation of the gear wheel E² by means of the pinion D² permitting the shaft E to continue to rotate in a direction to lower the load owing to 95 such rotation of the gear wheel E² releasing the brake. The lowering of the load is, however, controlled by the rotation of the power shaft A as the rotation of the shaft E faster 100 than the rotation of the gear wheel E² causes the brake to be applied through the axial movement of the gear wheel E² towards the friction disks owing to the engagement with a screw-thread f² on the shaft E with the 105 screw-thread within the hub on the gear wheel E².

110 When there is no load supported by the hoisting shaft E and it is desired to rotate such shaft in a direction to permit a load to be engaged, the power shaft A is rotated in a direction opposite to that indicated by the arrow, which through the rotation of the pinion D² rotates the gear wheel E² and moves the same axially upon the shaft E 115 until the stop f' on the hub of such gear wheel engages the lug f carried by the hoisting shaft. The continued rotation of the power shaft therefore positively rotates the hoisting shaft E in a direction to lower the usual cable 120 into a position to be engaged with a load.

125 In Fig. 4 I have illustrated a modified form of clutch which may be used in lieu of the clutch C above described. In such figure A' designates the power shaft upon which are loosely mounted pinions K' and K² between which is located the clutch L splined by means of a feather l upon the power shaft, as shown in Fig. 5. When the shaft is rotated in the direction indicated by the arrow the 130

engagement of the cam l^2 on the clutch member with the adjacent inclined surface on the hub of the pinion K' moves the clutch member axially so that the tooth l' on the opposite side thereof will engage the tooth k^2 on the hub of the pinion K^2 , thereby locking the pinion K^2 to rotate with the shaft A' . A rotation of the power shaft A' in an opposite direction causes the pinion K' to be locked to the shaft by reason of the clutch member being moved axially upon the shaft A' owing to the cam surface on the hub of the pinion K^2 engaging the adjacent cam surface on the clutch member L .

15 The operation of my improved hoisting mechanism is in all respects the same whether the form of clutch illustrated in Fig. 4 be employed or whether that illustrated in Figs. 1, 2, and 3 be used. It is therefore not necessary to further describe in detail the operation of the apparatus when the modified form 20 of clutch shown in Fig. 4 is employed.

While I have shown a fly wheel as connected with the load lowering pinion to retard the rotation thereof and thereby effect an axial movement of the gear wheel E^2 upon the hoisting shaft to apply the brake, yet it will be understood that I do not wish to limit myself to any specific means for this purpose 30 as it is obvious that other devices may be employed without departing from the spirit of my invention.

From the foregoing description it will be observed that I have invented an improved hoisting mechanism by means of which a load may be raised, lowered, or held at a fixed elevation, such result being accomplished by a power shaft, a hoisting shaft and interposed transmission gearing.

40 While I have described more or less precisely the details of construction, I do not wish to be understood as limiting myself thereto, as I contemplate changes in form, the proportion of parts, and the substitution 45 of equivalents, as circumstances may suggest, or render expedient without departing from the spirit of my invention.

Having now fully described my invention, what I claim as new and desire to secure by 50 Letters Patent is:

1. In a transmission mechanism for hoists, the combination with a rotary power shaft, of a hoisting shaft, gearing interposed between said shafts for rotating said hoisting shaft in a direction to raise a load, gearing interposed between said shafts for rotating said hoisting shaft in an opposite direction, and means actuated by an initial rotation of said hoisting shaft in a direction to lower the load 55 for locking said shaft against further rotation.

2. In a transmission mechanism for hoists, the combination with a rotary power shaft, of a hoisting shaft, gearing interposed between said shafts for rotating said hoisting

shaft in a direction to raise a load, gearing interposed between said shafts for rotating said hoisting shaft in an opposite direction, means actuated by an initial rotation of said hoisting shaft in a direction to lower the load 70 for locking said shaft against further rotation, and means for releasing said locking means actuated by an initial rotation of said power shaft in a direction to lower the load.

3. In a transmission mechanism for hoists, 75 the combination with a rotary power shaft, of a pair of pinions loosely surrounding said shaft, means for clutching one or the other of said pinions to said shaft according to its direction of rotation, a rotary hoisting shaft, a gear fixed upon said hoisting shaft in mesh with one of said pinions, a second gear wheel meshing with said second pinion and axially movable upon said hoisting shaft, a brake for preventing the rotation of the hoisting shaft 85 in a direction to lower a load, means for actuating said brake by an axial movement of said second gear wheel, and means for locking said second gear wheel to said hoisting shaft after a sufficient axial movement thereof to 90 release said brake.

4. In a transmission mechanism for hoists, the combination with a rotary power shaft, of a pair of pinions loosely surrounding said shaft, means for clutching one or the other of 95 said pinions to said shaft according to its direction of rotation, a rotary hoisting shaft, a gear fixed upon said hoisting shaft in mesh with one of said pinions, a second gear wheel meshing with said second pinion and having 100 an internally screw-threaded hub engaging a screw-thread on said hoisting shaft, a brake for controlling the rotation of said hoisting shaft, means for actuating said brake by the axial movement of said second gear wheel, and means for locking said second gear wheel to said hoisting shaft after a sufficient axial movement thereof to release said 105 brake.

5. In a transmission mechanism for hoists, 110 the combination with a rotary power shaft, of a pair of pinions loosely surrounding said shaft, means for clutching one or the other of said pinions to said shaft according to its direction of rotation, a rotary hoisting shaft, a gear fixed upon said hoisting shaft in mesh with one of said pinions, a second gear wheel meshing with said second pinion and axially movable upon said hoisting shaft, friction 115 disks surrounding and rotating with said hoisting shaft, a relatively stationary coöperating friction disk, said friction disks being interposed between said first and second gear wheels and relatively moved axially by the axial movement of said second gear wheel. 120

6. In a transmission mechanism for hoists, the combination with a casing, of a rotary power shaft extending through said casing, a pair of pinions loosely surrounding said shaft, means for clutching one or the other 125

- of said pinions to said shaft according to the direction of its rotation, a rotary hoisting shaft, a gear wheel fixed upon said hoisting shaft in mesh with one of said pinions, a second gear wheel axially movable on said hoisting shaft and in mesh with said second pinion, a friction disk rotating with said hoisting shaft, a coöperating friction disk held from rotation through engagement with said casing, said disks being interposed between said first and second gear wheels and moved axially into engagement with each other by the axial movement of said second gear wheel, and means for locking said second gear wheel to said hoisting shaft after a sufficient axial movement thereof to release said brake.
7. In a transmission mechanism for hoists the combination with a rotary power shaft, of a pair of pinions loosely surrounding said shaft, means for clutching one or the other of said pinions to said shaft according to the direction of its rotation, a rotary hoisting shaft, a gear fixed upon said hoisting shaft in mesh with one of said pinions, a second gear wheel meshing with the other of said pinions and axially movable upon said hoisting shaft, a fly wheel secured to said second pinion, and a brake interposed between said gear wheels and actuated by the axial movement of said second gear wheel and means for locking said second gear wheel to said hoisting shaft after a sufficient axial movement thereof to release said brake.
8. In a transmission mechanism for hoists, a hoisting shaft, a hoisting gear mounted on said shaft, a lowering gear mounted on said shaft so as to have a limited movement thereon, a brake for said shaft arranged to be applied by the lowering gear when the gear approaches one limit of its movement on the shaft, means associated with said shaft and said lowering gear for locking them together when the gear approaches the other limit of its movement relative to the shaft, a pinion for driving each of said gears, a driving shaft, and connections between the driving shaft and said pinions for effecting a driving engagement with one pinion or the other depending upon the direction of rotation of the driving shaft.
9. In a transmission mechanism for hoists, a hoisting shaft, a hoisting gear mounted on said shaft, a lowering gear mounted on said shaft so as to have a limited movement thereon, a brake for said shaft arranged to be applied by the lowering gear when the gear approaches one limit of its movement on the shaft, means associated with said shaft and said lowering gear for locking them together when the gear approaches the other limit of its movement relative to the shaft, a driving shaft, and means for effecting a driving connection with the driving shaft and the hoisting gear when the driving shaft is rotated in one direction and for effecting a driving connection between the driving shaft and the lowering gear when the driving shaft is rotated in the opposite direction at a speed equal to or greater than that which bears a predetermined relation to the speed of the lowering gear.
10. In a transmission mechanism for hoists, the combination with a rotary power shaft, of a hoisting shaft, gearing interposed between said shafts for rotating said hoisting shaft in a direction to raise a load, gearing interposed between said shafts for rotating said hoisting shaft in an opposite direction, means for locking said hoisting shaft against rotation actuated by an initial rotation of the hoisting shaft in the direction to lower the load and by a rotation of the hoisting shaft in the lowering direction at a greater speed than that produced by the power shaft, and means for releasing said locking means actuated by an initial rotation of said power shaft in a direction to lower the load.
- In testimony whereof, I sign this specification in the presence of two witnesses.
